UNITED STATES PATENT OFFICE.

ELKINS READ, OF LONACONING, MARYLAND.

RAIL-CLIP.

1,252,946.

Specification of Letters Patent.

Patented Jan. 8, 1918.

Application filed September 18, 1916. Serial No. 120,850.

To all whom it may concern:

Be it known that I, ELKINS READ, a citizen of the United States, residing at Lonaconing, in the county of Allegany and State of Maryland, have invented certain new and useful Improvements in Rail-Clips, of which the following is a specification.

This invention relates to an improved rail clip used in combination with an auxiliary extension rail, laid sidewise, and adapted for progressive, longitudinal movement for purposes of a temporary track extension.

The utility of this invention will be appreciated in mining operations where the car track may be progressively extended with the work until such intervals or points as will permit the placing of an additional standard length of rail to the main track. Heretofore the track extension was made only at such times when a standard length could be inserted, but now through the means of this invention the extension is made progressively with the work in the mines.

25 The use of this invention is not limited to mine tracks or to any particular section of rail or tie.

To distinguish the rails and simplify the description I use the term "track rail" or "track" to mean the usual rail upon which the cars travel as distinguished from the "extension rail" which is used for progressively extending such "track" or "track rail".

With these and other objects in view my invention consists in the novel construction, combination, association, and relative position of the parts and members shown in the accompanying drawings, hereinafter described, and particularly pointed out in the appended claims.

Referring to the drawing in which like reference characters indicate like or corresponding parts:

Figure 1 is a cross section of one of the track rails taken on line 1—1 of Fig. 2, showing the use of an extension rail of like section with my improved rail clip. Fig. 2 is a plan view showing my improved rail clip, and Fig. 3 is a section taken on line 50 3—3 of Fig. 2.

Fig. 4 illustrates a modified rail clip for use in combination with an extension rail of smaller section.

Referring to the illustrations, 5 indicates

one of the ordinary track rails mounted on 55 a steel tie 6 of any suitable cross section having a pair of raised clips 7 pressed out of the tie body with one side integral therewith and adapted to engage the outside of the flange 5^a. The other or inner side of the 60 flange 5^a is engaged by my improved rail clip 8 which as shown on the drawings, and is of rectangular heavy sheet steel having one end rolled (as at 8^a) to a substantially semi-circular cross section and formed with the 65 pressed lug 8^b adapted to engage the depression 6^a to positively retain the clip against lateral movement about the square head rivet 9 which securely connects the clip 8 to the tie 6. An upwardly pressed integral lug 10 70 positively maintains the head of the rivet 9 square with the clip sides to form an abutment for the flange 11^a of the extension rail 11 which is laid sidewise with the head toward the track rail and below the head 75 thereof.

It will be observed that one end 8^c of my improved clip 8 is slightly raised upwardly to overlap the track rail flange and that the edge 8^d thereof is formed substantially horizontal to support the extension rail head 11^b.

In the modified clip shown in Fig. 4 the construction is similar to that above described. Here however, the extension rail 11^x is of light weight and the edge 8^e is 85 bent substantially upwardly to support the head of the extension rail 11^x. Also in this case the pressed abutment lug 10^a is formed on the opposite side of the ordinary round head rivet 12 and is arranged to retain the 90 extension rail flange.

Preliminary to the insertion of a standard length section, the extension rail must be moved back to permit the turning of all clips, after which the permanent track rail 95 may be inserted and the clips forcibly moved to right line with the ties and track. The return movement of the clip over the added rail flange is aided by the curved corner 8^f which affords the gradual wedging 100 action of the clip over the flange.

In returning with a loaded car from the working end of a mine, the short wheel base of such cars permits the slight tilting of the same thereby easily raising the forward 105 wheels onto the higher car tracks.

It is thought that the foregoing description and illustrations clearly disclose the in-

vention, hence a more extended explanation is omitted.

I claim:

1. The combination with a track rail and an extension rail adapted for progressive longitudinal movement, of a rail clip having one end formed to support the head of said extension rail and means for retaining the flange of said extension rail. 5
2. The combination with a track rail and an extension rail laid sidewise and adapted for progressive longitudinal slidable movement along said track rail, of a rail clip having a portion thereof inclined and a substantially vertically disposed edge on said portion adapted to support the head of said extension rail, and means for confining said extension rail against lateral movement from said track rail. 10
3. The combination with a track rail and an extension rail laid sidewise with the head thereof adjacent said track rail and adapted for progressive slidable movement along said track rail, of a rail clip having a portion thereof inclined and a substantially horizontally disposed edge on said portion adapted to support the head of said extension rail, and means for confining said extension rail against lateral movement from said track rail comprising a rivet head in fixed relative position to the clip. 15
4. The combination with a track rail and an extension rail laid sidewise with the head thereof adjacent said track rail and adapted for progressive slidable movement along said track rail, of a rail clip having a portion thereof inclined and a substantially horizontally disposed edge on said portion adapted to support the head of said extension rail, and means for confining said extension rail against lateral movement from said track rail comprising an upwardly pressed portion of the clip body, having one side integral with the clip body. 20
5. The combination with a track rail and an extension rail laid sidewise with the head thereof adjacent said track rail and adapted for progressive slidable movement along said track rail, of a rail clip having a portion thereof inclined and a substantially vertically disposed edge on said portion adapted to support the head of said extension rail, and means for confining said extension rail against lateral movement from said track rail. 25
6. The combination with a track rail and an extension rail laid sidewise with the head thereof adjacent said track rail and adapted for progressive slidable movement along said track rail, of a rail clip having a portion thereof inclined and a substantially vertically disposed edge on said portion adapted to support the head of said extension rail, and means for confining said extension rail against lateral movement from said track rail comprising an upwardly pressed portion of the clip body, having one side integral with the clip body. 30
7. A rail clip comprising a steel plate having one end slightly inclined with the edge thereof formed to support the head of an auxiliary movable extension rail, said inclined end adapted to retain the flange of the stationary track rail, and means for retaining the flange of said extension rail. 35
8. A rail clip having one end slightly inclined with the edge thereof substantially horizontally disposed to support the head of an auxiliary movable extension rail, said inclined end retaining the flange of the stationary track rail, and means for retaining the flange of said extension rail. 40
9. A rail clip having one end slightly inclined with the edge thereof substantially horizontally disposed to support the side of the head of an auxiliary, movable extension rail, said inclined end retaining the flange of the stationary track rail, and an upwardly pressed portion of the clip body, integral therewith, arranged to confine said extension rail against movement from said track rail. 45
10. A rail clip having one end slightly inclined and the edge thereof substantially vertically disposed to support the head of a sidewise laid auxiliary extension rail, said inclined end overlapping the flange of the stationary track rail and an upwardly pressed portion of the clip body, integral therewith, arranged to confine said extension rail against movement from the track rail. 50

said track rail comprising a rivet head in fixed relative position to the clip. 55

6. The combination with a track rail and an extension rail laid sidewise with the head thereof adjacent said track rail and adapted for progressive slidable movement along said track rail, of a rail clip having a portion thereof inclined and a substantially vertically disposed edge on said portion adapted to support the head of said extension rail, and means for confining said extension rail against lateral movement from said track rail comprising an upwardly pressed portion of the clip body, having one side integral with the clip body. 60

7. A rail clip comprising a steel plate having one end slightly inclined with the edge thereof formed to support the head of an auxiliary movable extension rail, said inclined end adapted to retain the flange of the stationary track rail, and means for retaining the flange of said extension rail. 65

8. A rail clip having one end slightly inclined with the edge thereof substantially horizontally disposed to support the head of an auxiliary movable extension rail, said inclined end retaining the flange of the stationary track rail, and means for retaining the flange of said extension rail. 70

9. A rail clip having one end slightly inclined with the edge thereof substantially horizontally disposed to support the side of the head of an auxiliary, movable extension rail, said inclined end retaining the flange of the stationary track rail, and an upwardly pressed portion of the clip body, integral therewith, arranged to confine said extension rail against movement from said track rail. 75

10. A rail clip having one end slightly inclined and the edge thereof substantially vertically disposed to support the head of a sidewise laid auxiliary extension rail, said inclined end overlapping the flange of the stationary track rail and an upwardly pressed portion of the clip body, integral therewith, arranged to confine said extension rail against movement from the track rail. 80

In witness whereof, I have hereunto subscribed my name this 11th day of Sept., 1916.

ELKINS READ.
